(57) **CLAIM**

The ornamental design for an alcohol distillation apparatus, as shown and described.

DESCRIPTION

FIG. 1 is a front perspective view of the alcohol distillation apparatus showing the design;

FIG. 2 is a front, top perspective view thereof;

FIG. 3 is a rear view thereof

FIG. 4 is a front view thereof

FIG. 5 is a side view thereof; and,

FIG. 6 is a top view thereof.

The broken lines shown in the drawing views are included for the purpose of illustrating portions of the alcohol distillation apparatus that form no part of the claimed design.
